SAFETY STOP MECHANISM FOR KNITTING MACHINES

Ralph H. Goodison, Hatfield, Pa., assignor to
Sapphire Hosiery Corporation, New York, N. Y.,
a corporation of Delaware

Application November 30, 1949, Serial No. 130,255

7 Claims. (Cl. 66—157)

1

This invention relates to safety stop mechanisms for knitting machines, and more particularly to knitting machines such as are used in the manufacture of full-fashioned hosiery and similar articles.

A primary object of the invention is the provision of means for automatically stopping the machine if certain elements, which normally move in predetermined timed relationship, accidentally get out of step with each other as a result of mechanical failure or for any other reason. More specifically, the present invention is concerned with a safety switch associated with the slur bar and friction rod mechanisms of the knitting machine in such a manner as to become operative upon the falling out of step of said mechanisms in order to shut off the machine before completion of couloring, thereby preventing the yarn carriers from riding over and damaging the sinkers and dividers.

In full-fashioned knitting machines the knitting yarn is laid longitudinally of the sinker bed into the frontal notches of the sinkers and intervening dividers by means of a reciprocating yarn carrier operated in a suitable manner from the friction rod mechanism of the machine. The yarn carrier moves concurrently with but in advance of the slur cam or cock (mounted on the slur bar of the machine) which operates to progressively advance the sinkers and position the yarn in the intervals between adjacent pairs of needles. When the yarn carrier and slur cam have completed their traverse, the dividers are advanced in unison by the catchbar of the machine in order to uniformly apportion the yarn initially positioned by the sinkers between needles and the resultant loops are incorporated in the knitted article by actuation of the needle bar in the well-known manner. Following the laying of yarn for each course of knitting, the sinkers and dividers are simultaneously retracted preparatory to the laying of yarn for the succeeding course of knitting by means of the catchbar which is provided with a longitudinally extending groove for engaging upstanding butts on the sinkers and dividers. Since it is necessary for the yarn carrier of each sinker bed to precede the slur cock in laying the yarn for each course of knitting, it is necessary for the friction rod and the slur bar to reciprocate concurrently in predetermined timed relationship. If, however, the slur bar and friction rod should become out of step due to mechanical failure, it is necessary to have some means of shutting off the machine immediately before completion of couloring in or-

2

der to prevent the yarn carriers from riding over the sinker beds with resultant breakage or damaging of the sinkers and dividers.

The present invention contemplates the provision of a safety switch in an electrical circuit controlling the power source for the machine, the switch being operative to stop the machine immediately upon the falling out of step of the slur bar and friction rod mechanisms of the machine. In the preferred embodiment of the invention the switch may be mounted on the friction rod. The switch may be of the normally open type and will be held closed during proper functioning of the machine by means of a cam element secured between adjacent slur boxes and engaging a roller mounted on the switch plunger. In the event that the slur bar and friction rod fall out of step for any reason, the roller will ride off its associated cam element, thereby opening the electrical control circuit and stopping the machine.

The operating mechanism of the machine includes a coulier cam or cams driven from the main cam shaft of the machine by means of a clutch and suitable gearing. The coulier mechanism is provided for transforming the rotary motion of the cam shaft into the reciprocatory motion necessary for the operation of the slur bar, on which the slur cocks are mounted for actuation of the sinkers; and the friction rods which operate the yarn carrier rods to which the yarn carriers are secured. One of the reasons for the creation of the condition which is overcome by the arrangement of the present invention is the failure of the clutches which control the coulier mechanism to re-engage properly. The falling out of step of the friction rod and slur bar mechanism may also arise from other mechanical failure in the linkage system between said mechanisms and the coulier mechanism, such as stud breakage on the rocker arms or driving members interconnecting the rotary and reciprocatory mechanisms.

The foregoing objects as well as additional objects and advantages of the invention will be readily apparent in the course of the following detailed description taken in connection with the accompanying drawings which illustrate a preferred embodiment of the invention and wherein:

Fig. 1 is a rear view of a portion of a full-fashioned knitting machine incorporating the features of the invention;

Fig. 2 is a top plan view of a portion of the knitting machine on an enlarged scale, the friction rod being broken away in order to show the manner of mounting the switch cam element

between an adjacent pair of slur boxes on the slur bar;

Fig. 3 is a sectional view taken substantially on line 3—3 of Fig. 1; and

Fig. 4 is a fragmentary detail view illustrating the driving arrangement for the coulier mechanism.

In the drawings only the means necessary for a complete understanding of the present invention have been illustrated. While the catchbar has been illustrated, for example, the actuating mechanism therefor has been omitted for the sake of clarity, such mechanism and related mechanisms being conventional and well-known in the art.

Referring now to the drawings in greater detail, the full-fashioned knitting machine includes a framework comprising transverse frames 10, a rear beam 11 and a center bed 12. Center bed 12 supports a plurality of sinker beds 13, one of which is provided for each knitting section of the machine, and which extend longitudinally thereof. Two coulier mechanisms are provided, one for the right half and one for the left half of the machine, as seen in Fig. 1. Right coulier cam 14 is fixed to the rear end of a stub shaft 15 and is driven from the main camshaft of the machine by means of a clutch and gearing (see Fig. 4). Left coulier cam 14a is similarly mounted on stub shaft 15a and driven from the main cam shaft of the machine. Coulier cam 14 is connected to oscillate a driving member or rocker arm 16 pivoted to a beam bracket at 17. The upper end of rocker arm 16 carries a stud 18 for reciprocating a bracket 19 mounted on guide rod 20, said bracket being connected to a right friction rod 21 which in turn operates the yarn carrier rods 22 to which the yarn carriers 23 are secured.

The slur bar 24 extends over the entire length of the machine and is driven from the coulier cam 14 by means of a rocker arm 25 pivoted to a beam bracket at 26. Rocker arm 25 carries at its upper end a stud 27 for reciprocating a bracket 28 which is fixedly secured to slur bar 24 at 29, said bracket being also mounted on guide rod 20. Rocker arm 25 is operatively connected to rocker arm 16 by means of a linkage 30 in such a manner that rocker arm 16 will have a greater effective length assuring that the yarn carrier will always precede a respective slur box 31 mounted on slur bar 24.

Left coulier cam 14a is connected to oscillate a driving member or rocker arm 35 pivoted to a beam bracket at 36. The upper end of rocker arm 35 carries a stud 37 for reciprocating a bracket 38 slidably on guide rod 20. Bracket 38 is connected to left friction rod 21a which in turn operates the yarn carriers on the left side of the machine. Another rocker arm 39 may be pivotally linked to rocker arm 35, as shown on the left side of Fig. 1, in order to reciprocate the shock absorber bar 40, which does not however form part of the present invention.

It will be understood that the friction rods 21 and 21a operate the yarn carriers 23 for laying the yarn to be knitted while the slur bar operates the means for looping the yarn about the needles preparatory to the knitting operation. The yarn looping means include the sinkers 41 which are arranged in alternation with the dividers 42 in a plurality of transverse guide grooves formed in each sinker bed 13. The sinkers 41 are actuated in the usual manner by jacks 43 which are pivoted on a rod 44

and which are pushed forwardly by the slur cam 45 which is fixed to the reciprocating slur bar 24 by means of the slur cam box 31. The slur cam box 31 slides on a fixed guide bar 46, as shown in Figs. 2 and 3. In actual operation the slur cam 45 follows the motion of the yarn carrier 23 and pushes the sinkers 41 forwardly to sink the laid yarn between the knitting needles (not shown). When the yarn carrier 23 and the slur cam 45 have completed their traverse for one course of knitting, the catchbar 50 operates in the usual manner to advance the dividers 42 in order to uniformly apportion the yarn initially positioned by sinkers 41 between the needles. The resultant loops formed about the needles are incorporated in the knitted article by subsequent actuation of the needle bar of the machine. While the slur cam 45 is positioned outside the sinker bed 13 at the end of its traverse, catchbar 50 is lowered to engage the butts 41a of the sinkers 41 whereupon the sinkers 41 together with dividers 42 are retracted in unison preparatory to the laying of yarn for the succeeding course of knitting during the return stroke of the yarn carrier.

It will be noted that the yarn carrier 23 lays the yarn in the frontal receiving notches of the sinkers 41 and dividers 42 when said sinkers and dividers are in retracted position and that the sinkers are then progressively advanced concurrently with the motion of the yarn carrier by the action of the slur cam 45 against the sinker jacks 43. It follows therefore that the friction rods 21 and 21a (which operate the yarn carriers 23) and the slur bar 24 (upon which the slur cams 45 are mounted) must reciprocate concurrently in predetermined timed relationship so that each yarn carrier will precede a respective slur cam 45 in laying the yarn for each course of knitting. If, however, the slur bar 24 and friction rods 21 and 21a should fall out of step for any reason, it is necessary to have some means of shutting off the machine immediately and before completion of couliering in order to prevent the yarn carriers 23 from riding over the forwardly advanced sinkers 41 and dividers 42 with resultant breakage and damage.

According to the arrangement of the present invention a safety stop switch is provided in an electrical circuit controlling the drive motor of the machine, the switch being operative to stop the machine upon the falling out of step of the slur bar and friction rod mechanisms of the machine. In the preferred embodiment of the invention the switch 51 is preferably of the normally open type and is provided with a plunger 52 which carries at its lower end a roller 53, as best shown in Fig. 3. Switch 51 may be mounted on friction rod 21 by means of a bracket 54. A cam element or support 55 may be fixedly associated with the slur bar 24 in any suitable manner, as by being mounted between an adjacent pair of slur cam boxes 31. As long as the friction rod 21 remains in predetermined timed relationship with the slur bar 24 during the normal operation of the machine, roller 53 will be engaged by cam element 55 and the switch 51 will remain closed insuring uninterrupted operation of the drive motor (see Fig. 4). However, if for some reason of mechanical failure, the friction rod 21 should fall out of step with the slur bar 24, the roller 53 will ride off its associated cam element 55, thereby opening switch 51 and interrupting the circuit to the drive motor in order to stop the machine. Instantaneous stoppage of the motor

may be assured by the use of any suitable braking arrangement, such as a magnetic brake. By reason of the described arrangement the yarn carriers 23 will be prevented from accidentally riding over and damaging the sinkers 41 and dividers 42.

The conditions which might arise which would require immediate stoppage of the machine in order to prevent damage to the sinkers by the yarn carriers may be understood by referring to Fig. 1. It will be seen that a safety switch 51 is provided on the left friction rod 21a as well as on right friction rod 21. Right coulier cam 14 and left coulier cam 14a are driven from the main camshaft of the machine by means of clutches (see Fig. 4). The slur bar 24 extends over the entire length of the machine and is driven from the right coulier cam 14 which also drives the right friction rod 21. The left coulier cam 14a drives the left friction rod 21a which in turn operates the yarn carriers on the left side of the machine. If the clutches which control the right and left coulier cams 14 and 14a do not engage properly the left friction rod 21a will fall out of step with the slur bar 24 and switch 51 on the left side of the machine will then operate in the manner previously described to stop the machine. Other types of mechanical failure may result in the falling out of step of the friction rods 21 and 21a with respect to slur bar 24. Referring to the right side of the machine, for example, in the event of breakage of the studs 18 or 27 on driving members 16 and 25 respectively, the predetermined timed relationship between the right friction rod 21 and the slur bar 24 would be changed and the switch 51 on said friction rod would open and stop the machine. Similarly, the breakage of stud 37 on driving member 35 would result in the opening of switch 51 affixed to the left friction rod 21a and stoppage of the machine, thereby preventing the yarn carriers on the left side of the machine from riding over and damaging the sinkers.

Fig. 4 illustrates the driving arrangement for the right coulier cam 14 which is mounted on the stub shaft 15. Stub shaft 15 carries at its inner end a bevel gear 66 which meshes with a smaller bevel gear 65 rotatably mounted in a bracket secured to rear beam 11. Drive shaft 62 extends axially through bevel gear 65 and is connected to motor 60 by means of belting 61. Safety stop switch 51 is connected to the motor 60 by means of leads 67. A driving clutch member 64 is fixed to drive shaft 62 and operatively engages driven member 63, which is formed integrally with bevel gear 65, upon slight axial shifting of drive shaft 62 to the right as seen in Fig. 4. Operative driving engagement between clutch members 64 and 63 may be effected as by means of a pin 64a carried by member 64, said pin being insertable within a slot 63a of driven clutch member 63. Left coulier cam 14a is driven from drive shaft 62 by means of an arrangement similar to that shown in Fig. 4. Obviously the right and left cam wheels 14 and 14a may be operated from drive shaft 62 by means of other conventional clutch and gear arrangements.

Since certain modifications may be made in the safety stop mechanism of the invention without departing from the scope thereof, it is intended that all matter contained in the foregoing description and shown in the accompanying drawings be interpreted merely as illustrative and not in a limiting sense.

What is claimed is:

1. In a full-fashioned knitting machine hav-

ing a reciprocating slur bar, a friction rod concurrently reciprocated in predetermined timed relation therewith and a drive motor; a stop switch interposed between said slur bar and friction rod and arranged to be automatically actuated for stopping the motor upon accidental changing of the predetermined timed relation between said friction rod and said slur bar.

2. In a full-fashioned knitting machine having a reciprocating slur bar member, a friction rod member concurrently reciprocated in predetermined timed relation therewith and a drive motor; a stop switch secured to one of said reciprocating members, said switch being of the normally open type and having a contact plunger extending therefrom, a fixed abutment element carried by the other reciprocating member and normally urging said contact plunger to a switch closing position, said abutment element being movable out of engagement with said contact plunger for automatically opening said switch and stopping the motor upon accidental changing of the predetermined timed relation between said friction rod member and said slur bar member.

3. In a full-fashioned knitting machine having a reciprocating slur bar member, a friction rod member concurrently reciprocated in predetermined timed relation therewith and a drive motor; a stop switch secured to one of said reciprocating members, said switch being of the normally open type and having a contact plunger extending therefrom, a roller carried at the free end of said plunger, a cam element carried by the other reciprocating member and normally engaging said roller for urging said contact plunger to a switch closing position, said cam element being movable out of engagement with said roller for automatically opening the switch and stopping the motor upon accidental changing of the predetermined timed relation between said friction rod member and said slur bar member.

4. In a full-fashioned knitting machine having a reciprocating slur bar member, a friction rod member concurrently reciprocated in predetermined timed relation therewith and a drive motor; a stop switch secured to said friction rod member, said switch being of the normally open type and having a contact plunger depending therefrom a fixed abutment carried by said slur bar member and normally urging said contact plunger to a switch closing position, said abutment element being movable out of engagement with said contact plunger for automatically opening said switch and stopping the motor upon accidental changing of the predetermined timed relation between said friction rod member and said slur bar member.

5. In a full-fashioned knitting machine having a reciprocating slur bar member, a friction rod member concurrently reciprocated in predetermined timed relation therewith and a drive motor; a stop switch secured to said friction rod member, said switch being of the normally open type and having a contact plunger depending therefrom, a roller carried at the free end of said plunger, a cam element carried by said slur bar member and normally engaging said roller for urging said contact plunger to a switch closing position, said cam element being movable out of engagement with said roller for automatically opening the switch and stopping the motor upon accidental changing of the predetermined timed relation between said friction rod member and said slur bar member.

6. A full-fashioned knitting machine having a reciprocating slur bar extending over the entire length thereof, right and left friction rods concurrently reciprocated in predetermined timed relation with respect to said slur bar, a cam mechanism for simultaneously operating said slur bar and one of said friction rods, a separate cam mechanism for operating the opposite friction rod, a drive motor, a stop switch interposed between each of said friction rods and a respective portion of said slur bar on opposite sides of the machine, each of said switches being arranged to be automatically actuated for stopping the motor upon accidental changing of the predetermined timed relation between a respective friction rod and said slur bar.

7. A full-fashioned knitting machine having a reciprocating slur bar extending over the entire length thereof, right and left friction rods concurrently reciprocated in predetermined timed relation with respect to said slur bar, a cam mechanism for simultaneously operating said slur bar and one of said friction rods, a separate cam mechanism for operating the opposite friction

rod, a drive motor, a stop switch secured to each of said friction rods, each of said switches being of the normally open type and having a contact plunger depending therefrom, a roller carried at the free end of each plunger, and a pair of cam elements carried at opposite ends of said slur bar and respectively normally engaging the roller of a respective plunger for urging said plunger to a switch closing position, the roller of each switch being movable out of engagement with its normally associated cam element for automatically opening the switch and stopping the motor upon accidental changing of the predetermined timed relation between a respective friction rod and said slur bar.
